UNITED STATES PATENT OFFICE.

WILLIAM P. TALBOT, OF MILLBROOK, NEW YORK.

SHADE BRACKET.

Application filed January 23, 1925. Serial No. 4,133.

To all whom it may concern:

Be it known that I, WILLIAM P. TALBOT, a citizen of the United States of America, residing at Millbrook, Dutchess County, and State of New York, have invented certain new and useful Improvements in Shade Brackets, of which the following is a specification.

This invention relates to shade holders or brackets and in particular to a device which will prevent the end of the shade roller from leaving the bracket accidentally. An important object of the invention is to provide a locking member in combination with a shade holding bracket which will prevent the accidental displacement of the shade which in falling might injure a person as is often the case when roller shade cords break and the shade rolls up suddenly and jumps out of the bracket. The spring shaft end of the shade is the one which ordinarily fits into a bracket having an open ended slot; while the opposite end is held securely in a bracket having a hole therein and it is my intention to provide a lock on the spring shaft holding bracket to securely retain the shade in place.

A further object of the invention is to provide a locking member which can be removed or inserted without screwing or the use of any fastening medium and one which can not be accidentally removed by the striking thereagainst of any part of the shade or outside agent.

A still further object is to provide a shade lock which will keep the shade roller horizontal at all times thus preventing the uneven winding up of the shade which causes wear to the edges thereof.

A still further object of the invention is to provide a lock which when double shades are used will prevent one of the shades from causing the one adjacent thereto to leave its brackets.

Referring to the drawing wherein I have shown a preferred embodiment of my invention;

Figure 1 is view in perspective of the spring shaft receiving bracket provided with my improved lock, the shade being shown in outline;

Figure 2 is a view in side elevation of a bracket adapted to be placed on the window frame and projecting at right angles to the shade, and embodying a particular shape of locking pin;

Figure 3 is a top plan view of the bracket and portion of the window shade as shown in Figure 2.

Figure 4 is a view in front elevation of the bracket as seen in Fig. 2.

Figure 5 is an enlarged view taken of a form of locking pin which can be used in either type of bracket, part of the bracket being shown in a section taken on line 5—5 of Figure 1.

Figure 6 is an enlarged view of a modified form of locking pin, the lugs being similar to those illustrated in Figs. 2, 3 and 4.

Referring to the drawing, 5 indicates a part of a window shade of the usual type embodying the roller 6 and projecting spring shaft 7 which is usually flat or rectangular, in shape, and adapted to fit into an opening or nest 8 in the protuberant portion 9 of a bracket 10.

The bracket is held in position on the window frame 11 by screws 12 or other fastening means which pass through the extended flat end portions or feet 13 of the bracket. The protuberant portion 9 is provided to allow for various lengths of shade, the shaft 7 extending therewith a certain distance depending upon the width of the shade 5.

The opening 8 as shown in Figure 1 is connected to the outer edge of the portion 9 through the medium of a slot 14 which is angularly disposed. The opening may be also disposed as an angle as shown or it may be vertical. It is slightly larger than the shaft 7 and the slot 14 is wide enough to allow the shaft 7 to pass therethrough to be subsequently seated in the opening 8.

In order to prevent any release of the shaft 7 I provide a flat portion 15 on the upper outer edge of slot 14 and a boss 16 directly thereunder on the inner side of the lower edge of the slot 14 so that a pin or rivet 17 may be passed through an opening 18 in the flat portion 15 and have its lower end disposed in a bore 19 in the boss 16, as shown in Figure 5. It will be noted in this instance that the pin 17 is provided at its upper end with a knob 20, while the body portion 21 thereof is reduced in that part lying within the flat portion 15, the lower end being cut down to provide a spindle 22 which projects into the bore 19 to have a loose play therein. When the shaft 7 has a tendency to jump out of the

100

105

110

nest or opening 8 it strikes the body of the pin causing it to assume an angular position and the reduced portion edges prevent its raising out of the hole 18. It therefore prevents the shaft from leaving the bracket member.

In Figures 2, 3, 4 and 5 I have illustrated a bracket 23 which projects outwardly from the window frame and at right angles to the shade and which is slotted horizontally as at 24, it being understood that the slot could be vertically disposed if desired. The enlarged slotted part 25 of the bracket adjacent the outer ends of the slot 24 is flattened to provide the lugs 25^a having openings 26 therein through which is adapted to pass the pin 27 having a ball end 28 and reduced portions 29 adjacent its upper and lower ends the portions 29 being disposed so that their centers are in a plane with the lugs. Thus when the shaft 7 of the shade tends to leave the slot 24 it strikes the pin and the edge of the lug is engaged in the reduced portion 29 of the pin thereby preventing the latter from raising out of the bracket to release the shade.

While I have not illustrated the opposite mating piece of the bracket, it will be understood that it may be any type in present use adapted for holding the round portion of the shade roller end plate.

The rounded knobs on top of the locking pins prevent any accidental upward movement of the pin by allowing any object which strikes said knobs to slide off without raising the pins out of position.

Thus it will be seen that I have provided a window shade lock which will prevent a shade from leaving its fastenings accidentally to thereby strike a person, and also a lock which will hold the shade roller in horizontal position to prevent uneven winding up of the shade itself. The locking bracket can be made in large quantities and at small cost and can be applied in short

time, the locking pin being simply dropped into place after the shaft 7 has been placed in its bracket.

Having described my invention what I claim is:—

1. A window shade bracket having an opening adapted to receive the end of the shade roller shaft, said opening having an extended portion, a pin member disposed across the extended portion of said opening and movably held in said bracket, and means constituting a shaped end on said pin for preventing its accidental removal from position across said opening.

2. A locking device for window shades comprising a bracket having a slot therein for the reception of one end of the shade, a pin member disposed in said bracket so that it closes the entrance to said slot, said pin member having a portion thereof reduced in diameter whereby its accidental removal from the bracket will be prevented.

3. A locking bracket for window shades having therein a shaft receiving slot, a pin fitting in said bracket and closing the entrance to said slot, said pin having its body portion reduced in diameter at a point adjacent the top thereof, and at its lower end.

4. A locking member for window shades or the like comprising a bracket having formed therein upper and lower pin receiving portions, a pin passing through said portions, said pin body being reduced in diameter below said upper bracket portion and further reduced in diameter in the part lying within the lower bracket portion.

5. A window shade bracket having an opening adapted to receive the end of the shade roller shaft, a headed pin member disposed across said opening and movably held in said bracket, and means formed integral on the end of said pin for preventing its accidental removal.

WILLIAM P. TALBOT.
